UNITED STATES PATENT OFFICE

JAMES RUSSELL DOHERTY, OF OAK PARK, ILLINOIS

FURNACE

Application filed August 1, 1927. Serial No. 209,861.

This invention relates to furnaces and more particularly to means for increasing the efficiency thereof.

One object of the present invention is to simplify the construction and improve the efficiency of devices of the character mentioned.

Another object of the invention is the provision of simple means for insuring the complete combustion of the generated fuel gases.

Another object is the provision of means for controlling the admission and temperature of auxiliary air to the combustion chamber so as to procure the best possible oxidation of the gases therein.

Still another object is the provision of means for effecting secondary ignition of the combustible gases prior to the discharge thereof to the atmosphere.

A further object is the provision of means whereby uncombined gases passing out of the fire-box may be readily ignited in a secondary combustion chamber to extract therefrom all available thermal heat prior to its discharge to the atmosphere.

A still further object of the invention is the provision of means whereby the intense heat in a secondary combustion chamber may be utilized for the combustion of refuse or waste matter.

Other objects and advantages will appear from the following description of an illustrated embodiment of the present invention.

In the drawings:

Figure 1 is a sectional view in elevation of a furnace embodying the features of the present invention, a part thereof being broken away to more clearly illustrate the structure thereof;

Figure 2 is a sectional view taken substantially along line 2-2 of Figure 1; and

Figure 3 is a fragmentary rear view in elevation of the structure shown in Figure 1.

The structure selected for illustration comprises a furnace having the usual intermediate sections 10 disposed between a rear section 11 and a front plate section 12, the sections being secured together in any suitable manner to form an integral furnace having the usual combustion chamber 13 with the rear section

14 thereof constituting, in this instance, a secondary combustion chamber.

The front section 12 has the usual fire-box doors, shaker arms, and other accessories of standard construction associated therewith in the usual manner.

Each section 10 has a chamber 15 of irregular configuration defining a large surface area, in this instance of T-shaped cross-section disposed adjacent each other to constitute the roof of the fire-box or combustion chamber. A plurality of irregular chambers 16 disposed rearwardly of the chambers 15, are arranged in spaced relation to permit the gases to pass therebetween into a flue passage 17 in the upper part of the furnace, the flue passage 17 preferably defining a curvilinear path prior to establishing communication with a chimney of suitable construction.

A grate 18 of standard construction is horizontally disposed within the forward portion of the combustion chamber 13, it terminating in a bridge wall 19 which extends vertically midway of the ceiling defined by the chambers 15. Obviously, the height thereof may be varied according to the particular characteristics desired, it having been found, however, that a wall proportioned substantially as illustrated herein is productive of good results. Near the lower portion of the bridge wall 19, a plurality of apertures 20 are provided to permit a portion of the gases issuing from the burning fuel to pass therethrough into the secondary combustion chamber 14.

A water curtain 21 is disposed rearwardly of the bridge wall 19, it being arranged to depend from a section 10 in spaced relation with the bridge wall 19. A right angular projection 22 (Figures 1 and 2) is formed integral with the chamber 21 constituting a water curtain, to support a column of refractory bricks or other fire resisting material 23 thereon, the lowermost bricks 23 being L-shaped to define a continuous transverse passageway 24 across the water curtain.

The passage 24 communicates with the exterior of the furnace on either side thereof to admit air to be introduced within the combustion chamber subsequent to the tem-

perature regulation thereof by contacting with the water curtain 21. A plurality of ports 24 are provided in the refractory wall 23 which shields the water curtain 21 from the excess heat of the gases and helps break up the carbon therein, the ports 25 communicating with the air conducting passage 24 whereby an auxiliary supply of air is furnished along the entire width of the water curtain to effect complete combustion and disintegration of the carbon contained in the combustion gases. The passage 24 extends exteriorly of the furnace 10 (Figure 2), it being valved by any suitable means such as the members 26 which control the air admitted from either or both sides of the furnace to the combustion chamber 14, the air contacting with the water curtain 21 which regulates its temperature so that the admitted air will be sufficiently cool to furnish a maximum amount of oxygen per unit volume, but not cool enough to decrease the temperature of the gases sufficiently to effect a material decrease in thermal efficiency. The auxiliary air supply should be sufficiently heated to produce a rapid chemical reaction with the carbon in the furnace gases.

It is to be noted that a stream of air may be discharged from the surface of the wall 19 which confronts the ports 20 to more effectively oxidize the combustion gases passing therebetween. To accomplish this end, the structural arrangement disclosed in connection with the air passage 24 may be embodied in the wall 19, the proposed passages therein being supplied with air from the exterior of the furnace in any appropriate manner.

Immediately behind the bridge or baffle wall 19 is a horizontal layer of refractory bricks forming a floor 27 supported by a plate 28, the floor terminating in an arch 29. Immediately in advance of the arch 29 are a plurality of apertures 30 extending through the floor 27 to receive pipes 31 which communicate with a gas line 32 connected to a suitable source of supply (not shown). These pipes constitute means whereby a pilot light or a plurality of pilot lights may be provided so that the unconsumed gases from the fire-box 13 and the air from the water curtain 21 may be ignited. The pilot light is required only when the floor 27 and arch 29 are cold or at a temperature unable to effect combustion of the gases issuing from the combustion chamber. Continued operation of the furnace, effects incandescence to the refractory bricks constituting the floor 27 and arch 29 to readily ignite the uncombined gases whenever such gases are too cold to unite autogeneously. It is obvious that the need for providing means for re-igniting the gases in the secondary combustion chamber exists only when such gases are too cold to ignite themselves, as, for example, when a fresh

blanket of coal has been placed upon the grate 18 or when a new fire is started.

The apertures 30 surrounding the pipes 31 permit an updraft of air therethrough to maintain the pipes 30 sufficiently cool to minimize the danger of oxidation or destruction thereof. The updraft of air at this point is also beneficial in assisting in the commingling of the air and combustion gases passing underneath the water curtain 21. In addition, it has the effect of introducing a still further supply of air which assists in the combustion of the fuel gases. The invention contemplates any usual means for shutting off the supply of air to the apertures 30.

A door 35 is provided in the rear wall of the furnace for enabling entry to the secondary combustion chamber 14 by the removal of a portion of the brick in the arch 29. The supporting plate 28 is perforated at this point to form a grate 36 which serves as an auxiliary fire-box designed for the purpose of burning garbage or other refuse. The garbage is placed on the grate 36 when in a moist condition, at which time it is unfit for burning. The intense heat in proximity to the arch 29, resulting from the secondary combustion of gases, quickly dries the garbage. Further, the rapid movement of the gases carries away all odor from said garbage, it being entirely ignited by the heat of the combustion chamber, or it may be ignited by opening a door 37 disposed below the door 35 to admit air through the grate 36. The door 37 has the added function of enabling the furnace underneath the secondary combustion chamber to be cleaned as may be necessary at intervals.

The presence of the bridge wall 19 in front of the water curtain 21 has the effect of imparting a whirling motion to the gases passing thereover. This whirling motion is then partially interfered with by the flow of gases through the apertures 20, the gases passing through the apertures 20 impacting with the gases passing over the bridge wall 19 at high velocity, thereby effecting a further agitation thereof. At this point, additional air is introduced, which also contributes to the motion of the twirling gases. Subsequently the updraft of air through the apertures 20 will assist the desired agitation and commingling, while the slope of the arch 29 also contributes thereto to intimately mix the combustion gases with the additional air, insuring further and complete combustion of the gases.

A furnace embodying the features illustrated and described herein, produced an intense heat with an unusually high thermal efficiency, it being almost impossible to make such a furnace "smoke" in any way, since all of the carbon and gases distilled from the coal are entirely burned in the secondary combustion chamber 14. A white glow ex-

tended from the fire curtain 21 along the arch 29 and disappeared through the apertures between the sections 16, which is indicative of complete combustion.

5 Various changes may be made in the embodiment of the invention herein specifically described without departing from or sacrificing any of the advantages thereof as defined in the appended claims.

10 I claim:

1. In a furnace, a combustion chamber in the front portion thereof, a grate in said chamber, a bridge wall upstanding from the rear of said grate, a water curtain rearwardly 15 of said bridge wall and depending therebelow to provide a baffle, air conducting means associated with said water curtain and discharging air therefrom below the top level of said bridge wall, and a secondary combustion chamber to the rear of said water curtain and said bridge wall, there being apertures in said bridge wall beneath the lower level of said water curtain to admit the passage of combustion vapors directly to said 25 secondary combustion chamber.

2. In a furnace, a combustion chamber in the front portion thereof, a grate in said chamber, a bridge wall upstanding from the rear of said grate and projecting the major 20 distance from said grate to the top of said furnace, a water curtain depending from the roof of said furnace to a level well below the horizontal plane of the top of said bridge wall, air conducting means associated with 25 said water curtain and adapted to discharge water cooled air below the level of the top of said bridge wall, and a secondary combustion chamber to the rear of said water curtain and said bridge wall, said secondary 30 combustion chamber having a refractory floor, whereby the combustion vapors from said grate to the flue of said furnace are required to pursue a serpentine course, there being apertures in said bridge wall beneath 35 the level of the lower edge of said water curtain to admit the passage of a limited volume of combustion vapors directly to said secondary combustion chamber.

JAMES RUSSELL DOHERTY.
